UNITED STATES PATENT OFFICE.

JAMES NELSON SIMMS, OF CHICAGO, ILLINOIS.

DESIGN FOR A CLOCK-CASE.

50,152.

Specification for Design.

Patented Jan. 9, 1917.

Application filed January 3, 1916. Serial No. 70,063. Term of patent 7 years.

To all whom it may concern:

Be it known that I, JAMES NELSON SIMMS, a citizen of the United States, residing at Chicago, in the county of Cook and State of Illinois, have invented a new, original, and ornamental Design for Clock-Cases, of which the following is a specification, reference being had to the accompanying drawing, forming a part thereof.

The figure is a plan view of a clock case, showing my design.

I claim:

The ornamental design for a clock case as shown.

JAMES NELSON SIMMS.
